MACHINE FOR HONING CAMSHAFTS

Carl A. Gerlach, Spring Lake, Mich., assignor to
 Muskegon Motor Specialties Company, Muskegon, Mich., a corporation of Delaware

Application April 17, 1944, Serial No. 531,387

16 Claims. (Cl. 51—3)

This invention relates to machines for honing cam shafts, particularly cam shafts for internal combustion engines of the multi-cylinder type.

Cam shafts in modern internal combustion engines are usually integral structures, such as forgings or castings, on which the intake valve controlling cams and the exhaust valve controlling cams are arranged in pairs with the cams of the pairs close together. These shafts, after the final machining operations, are usually subjected to honing of the profile surfaces of the cams or honing of shaft portions between cam pairs which are to be received in bearings for supporting the shafts in proper alignment. The general object of my invention is to produce a machine for efficiently, accurately and simultaneously honing the cam surfaces or bearing surfaces, or both.

More in detail an important object of the invention is to produce a machine comprising honing units for the respective cam surfaces and the bearing surfaces.

Another object is to provide master cam shafts and supports on which the cam honing units are mounted to be operated by the cams on the master shafts.

A further object is to produce a machine in which the cam shaft and master shafts are rotated at the same speed, and with the cam shaft subjected to axial reciprocation during rotation thereof.

Still a further object is to produce a machine in which the honing units for the ignition cams and the honing units for the exhaust cams are respectively arranged in separate planes extending through the axis of the cam shaft so that the honing elements on the intake cam honing units and the honing elements on the exhaust cam honing units may be applied to the close together intake and exhaust cams of the cam pairs on the shaft.

Another object is to provide an arrangement in which the bearing honing units are in a plane annularly displaced from the planes of the intake cam and exhaust cam honing units.

Another object is to provide separate support for the intake cam honing units, the exhaust cam honing units, and the shaft bearing honing units, on which supports the respective units are mounted for ready adjustment into the proper position for honing engagement with the respective surfaces to be honed, whereby setting may be readily made for honing of shafts with different cam arrangement thereon.

Still a further object is to adapt the supports for the respective honing unit assemblies for

movement to carry the units out of or into the honing position so that cam shafts to be honed may be readily inserted in the machine for honing and readily removed therefrom after the honing operation.

Further objects and features of the invention will become apparent from the following specification in connection with the accompanying drawings, in which drawings:

10 Figure 1 is a left end elevation of the machine;

Figure 2 is a front view of the machine in section on plane II—II of Figure 1;

15 Figure 3 is a section on plane III—III, Figure 2;

Figure 4 is an enlarged section on plane IV—IV, Figure 2;

Figure 5 is a section on plane V—V, Figure 4;

20 Figure 6 is a section on plane VI—VI, Figure 2;

Figures 7 and 8 are enlarged sections on plane VII—VII, Figure 1, of the left and right hand structures between which the shafts to be honed are mounted;

25 Figure 9 is a section on plane IX—IX, Figure 7;

Figure 10 is a section on plane X—X, Figure 8;

Figure 11 is an enlarged section on plane XI—XI, Figure 2, of one of the cam honing units;

30 Figure 12 is an enlarged section on plane XII—XII, Figure 2, of one of the bearing honing units; and

Figure 13 is a section on plane XIII—XIII of Figure 12.

35 The supporting structure for the cam shafts W to be honed comprises the top plates 8 and 9 mounted on and extending across the side walls 11 and 12 of the machine supporting framework, the plates being separated by the space

40 13. At the left side of the machine (Figures 2, 7 and 9) a head 13 is mounted on the plates 8 and 9 to be reciprocated longitudinally thereon, the head being guided by guide bars 14 and being held to the plates by top bars 15 which engage

45 the feet 16 on the head. At the right side of the machine (Figures 8 and 10) a head 17 is mounted on the plates for longitudinal reciprocation thereon with the guide bar 18 and top bars 19 engaging the feet 20 on the head. The

50 two heads 13 and 17 are secured to and connected by side bars 21 and 22 so that the two heads may reciprocate together longitudinally on the plates 8 and 9 between the guide bars 14, 15 and 18, 19, respectively, which bars may be se-

55

cured to the plates as by screws 23 and 24, respectively.

The shafts W to be honed are mounted and centered between the heads 13 and 17 for rotation and for axial reciprocation with the head structure. The mechanism for reciprocating the head structure is best shown on Figures 2, 8 and 10. Mounted on the side wall 12 of the machine framework is a bracket 25 from which extend bearing arms 26 for journaling a shaft 27 mounting at its outer end a pulley 28. This pulley is driven through a belt 29 by an electric motor 30 mounted on the side wall 12. The front end of the shaft 27 terminates in a head 31 from which extends the eccentric crank pin 32 having the cam roller 33 thereon. A bell crank lever 35 is fulcrumed on a shaft 36 just inside of the side wall 12 with its horizontal leg extending outwardly through the passageway 37 in the side wall and the bracket 25 and terminating at its outer end in the slot 38 which receives the cam roller 33. The vertical leg of the lever extends upwardly through the space 10 between the plates 8 and 9 and terminates in the slot 39 which receives the roller 40 on the pins 41 extending through the head 17. Thus, as the pulley 28 is rotated, the heads 17 and 13 connected by the bars 21 and 22 will reciprocate as a unit on the plates 8 and 9 for axial reciprocation of the cam shaft supported by the heads.

Referring to Figures 7 and 9, a driving spindle 42 extends through and is journalled in the head 13 and terminates at its inner end in the head 43. The outer end of the spindle 42 extends into a housing structure 44 which is supported on a bracket 45 (Figure 1) mounted on the side wall 11 of the machine supporting framework. Within the housing structure 44, the spindle receives the hub 46 of a worm gear 47, the hub being journalled in the housing but held against axial movement therein, suitable key structure 48 connecting the spindle to the hub so that the spindle must rotate with the hub but may shift axially therein. The spindle is journalled in bushing 49 and 50 held in the ends of the head 13, the shoulder 51 on the spindle engaging the inner bushing, and a collar 52 secured to the spindle engaging the outer bushing so that the spindle is held against axial movement in the head 13. Upon reciprocation of the head structures 13, 17 on the plates 8 and 9 by operation of the pulley 28, the outer end of the spindle moves inwardly and outwardly in the housing structure 44 and will be rotated by the gear 47. This rotation of the spindle is communicated to the cam shaft W to be honed.

Detachably secured to the inner face of the spindle head 43 by its flange 53 is the chuck collar 54 having a tapered bore for receiving the tapered end 55 of the cam shaft W. This end of the cam shaft has a centering recess 56 therein for receiving the centering pin 57 seated in the tapering inner end of the spindle bore, the cam shaft being thus held in axial alignment with the spindle. The shaft end 55 is provided with a keyway 57 for reception of a key 58 rotatable in the slot 59 in the chuck collar on a pin 60. The key has the upwardly extending arm 61 through which threads a screw 62 for abutment against the chuck collar flange 53 so that the key may be securely seated in the keyway 57 for communication of the rotation of the spindle 42 to the cam shaft.

At its right end, each cam shaft to be honed has a centering recess 63 for receiving the cen-

tering point on a head 64 whose tapered stem 65 extends into the bore of a sleeve 66 slidably axially in the head 17 but held by a key 67 against rotary movement. The outer end of the bore of the sleeve 66 is threaded to receive the threaded end of a screw 68 which is journalled in the outer end of the head and provided with a handwheel 69. Upon turning of this handwheel 69 the sleeve 66 may be shifted axially in the head 17 for engagement of the point of the centering head 64 in the centering recess 63 of the shaft to be honed so that the shaft will be held in axial alignment with the spindle 42.

The shafts W to be honed are shown as for six cylinder engines, each shaft having six pairs of cams integral therewith and each pair comprising an intake valve controlling cam I and an exhaust valve controlling cam E. For each intake cam I a honing unit HI is provided, and for each exhaust cam a honing unit HE is provided. As the intake and exhaust cams of each pair are quite close together, the units HI are arranged in one row and the mounting units HE are arranged in another row, with the two rows in planes at an angle with each other. As shown, the plane of the row of mounting units HI is inclined at substantially 45° from the vertical plane passing through the axis of the shaft to be honed, while the plane of the row of the units HE is inclined at substantially 45° in the opposite direction from the vertical plane, see Figures 1, 3 and 4. The honing units HI are operated by one master cam shaft MI, and the units HE are operated by a master cam shaft ME. These master shafts and the shaft W to be honed are all rotated at the same speed, and during such rotation the shaft W is reciprocated axially for reciprocation of the surfaces of the cams thereon relative to the honing wheels on the honing units, as will be described more in detail later.

The units HI are supported on a base plate 70 extending across the rear part of the machine and mounted at its ends on inclined bars 71 and 72 supported by the rear wall 13 of the machine framework. The units HE are supported on a base plate 74 extending across the front part of the machine and mounted on inclined bars 75 and 76 supported by the front wall 11 of the machine framework.

Mounted on the supporting base 70 for the units HI, at the upper corners thereof, are the centering and driving head 78 for the master shaft MI and the centering tail head 79 for the shaft. The arrangement within the tail head 79 is substantially like that in the tail head 17 for the shaft W to be honed, turning of the handwheel 80 controlling the setting of the centering point 81 in the centering recess in the shaft MI. The arrangement in the driving head 78 may be substantially like that in the head 13 for the shaft W except that the spindle 82 has secured to its outer end a worm gear 83 (Figure 1) within the housing 84 secured to the supporting base 70. At its inner end the spindle has the chuck collar 85 which receives the end of the master shaft MI to be keyed thereto by a key 86 in the same manner as the shaft W is keyed to the driving spindle 42.

On the supporting base 74 for the units HE are mounted the driving head 87 for the spindle 88 for the master shaft ME, and a tail centering head like the tail centering head 79 for the shaft MI. The driving spindle 88 for the shaft ME has secured to its outer end the worm gear 89 located within the housing 90 supported on

the base 74. The master shaft MI has the cams I' thereon and the shaft is centered between its heads 78 and 79 so that these cams are in radial alignment with the cams I on the shafts W to be honed. The master shaft ME has the cams E' thereon and this shaft is centered between its heads with the cams in alignment with the cams E on the shafts W to be honed.

The driving mechanism for the master shafts and the shaft to be honed is best shown on Figures 1 and 2. A drive shaft 91 extends through the housing structure 92 which is mounted on the support 45 and of which the housing structure 44 may be an integral part, this housing structure 44 housing the driving gear 47 for the shaft to be honed. The upper end of the shaft extends through the housing portion 94 which forms part of the housing 84 for the driving gear 83 of the spindle 82 for the master shaft MI. Within the housing portion 94 the shaft 91 mounts a worm pinion 95 which meshes the gear 83, the worm pinion being held in the housing against axial movement therein.

Within the housing 92, the shaft 91 mounts a worm pinion 96 which meshes the gear 47 in the housing 44 for drive of the spindle for the shaft to be honed. Within the housing 92 the shaft 91 also mounts a bevel gear 97 which meshes the bevel gear 98 at the lower end of the shaft 99 which extends through the housing portion 100 forming part of the housing 92 in which is the gear 89 for driving the spindle 88 for the master shaft ME. Within the housing 100 is the worm pinion 101 meshing the gear 89. The lower end of the drive shaft 91 is journaled in a bearing 102 on the end wall 11, and the shaft is driven through a belt 103 by an electric motor 104 mounted on the end wall 11. The gearing connection between the drive shaft 91 and the three cam shafts is such that these three shafts will be rotated at the same speed.

The honing units HI and HE are of the same construction, one of the units HI being shown on Figure 11. Each unit comprises a body 105 having the bore 106 therethrough into which extends the plunger 107 through a bushing 108 in the upper end of the bore. The neck 109 on the plunger receives the tail frame 110 secured thereto by a pin 111. This tail frame has sliding and guide engagement with the upper portion 112 of the body 105 so that the reciprocating movement of the plunger will be guided but the frame and the plunger will be held against rotary movement.

The plunger 107 has the lower end 113 of reduced diameter between which and the plunger body is the flange portion 114 which fits the bore 106 and between which and the bushing 108 is interposed a compression spring 115 which tends to hold the plunger inwardly in the bore. Inserted in the lower end of the bore 106 is a bushing 116 through which extends a cylindrical bar 117 having the bore 122 receiving the plunger end 113 and terminating above the bushing in a head 118 which fits the bore 106. The head 118 has a slot 119 for a key 120 which is secured to the end 113 as by a screw 121. The key 120 is of a width to fit the width of the slot 119 so that the bar 117 will be held against rotational movement, but the length of the slot is such that the bar 117 may move axially relative to the plunger end 113, there being sufficient clearance between the bushing 116 and the plunger flange 114 for such axial movement. In the bore 122 in the bar 117 a compression spring 123 is interposed between the bottom of the bore and the

end 113 of the plunger 107 and this spring tends to shift the bar 117 outwardly. In the lower end of the bar 117 is a diametrically extending slot 124 for receiving a honing wheel 125 supported on the pin 126. When the unit is in service on the machine, the honing wheel 125 will be in engagement with one of the cams on the cam shaft to be honed. Figure 11 shows one of the units HI with the honing wheel in engagement with one of the intake cams I on the shaft W.

The tail frame 110 of the plunger 107 has at its upper end an arm 127 extending therefrom on which is journaled a cam roller 128 for engagement with a cam on one of the master cam shafts. Figure 11 shows the roller in engagement with one of the cams I' on the master shaft MI. As the master shafts and the shaft to be honed rotate at the same rate, the cams on the master shafts and the plunger springs 115 will cooperate to reciprocate the plungers 107 for engagement of the honing wheels with the surfaces of the cams to be honed. The pressure of the springs 115 on the flanges 114 of the plungers 117 will hold the cam rollers 128 intimately against the master shaft cams, while the springs 123 will urge the bars 117 outwardly for the proper honing pressure engagement of the honing wheels with the respective cams to be honed.

Referring to Figures 2, 4, 5 and 11, the supporting base 70 for the honing units HI has the dovetail boss or rail 129 extending longitudinally thereon for receiving the recesses 130 in the bottom of the body 105 of the units, gib keys 131 set by screws 132 holding the units in position on the rail. With this arrangement the units HI may be accurately set on the supporting base 70 for alignment of cam rollers 128 and honing wheels 125 with the respective cams on the master shaft MI and the shaft to be honed. A similar dovetail boss or gib rail 133 is provided on the supporting base 74 for the honing units HE for adjustment of the units relative to the master shaft ME and the shaft W to be honed. As the master shafts and the shaft to be honed are rotated, the honing wheels 125 will roll on the engaged cam surfaces under pressure of the springs 123 in the honing units, and during rotation of the shaft W it is axially reciprocated as has already been described. The extent of this axial reciprocation is such that the engaged cam surfaces will never be moved out of engagement with the respective honing wheels, and this reciprocation of the cam surfaces relative to the honing wheels will result in honing abrasion of the cam surfaces by the wheels. The wheels are of emery or other suitable honing material or composition and of abrasive characteristics depending upon the honing desired. All the cams on a shaft are thus simultaneously honed to the desired degree and accuracy.

Honing units are also provided for honing the cylindrical bearing portions of the cam shafts at their ends and between the cam pairs thereon. Referring to Figures 4 and 12, each bearing honing unit HB comprises a body 134 having an extension 135 at the top thereof which has the bore 136 therethrough. Seated in this bore is the bushing 137 through which extends the cylindrical plunger 138 on whose top is supported a head 139 having a recess 140 for receiving a block 141 of honing material. A clamping plate 142 on the head serves to hold the mounting block securely seated in the recess. The outer surface of the honing block is of arcuate cross section to the

radius of the bearing portion 143 to be honed by the block, the length of the block corresponding to the length of the bearing surface between cam groups to be honed by the block.

Below the extension 135 on the body 134 is an arm 144 through which threads a screw 145 which projects into the lower end of the bore 146 in the plunger 138, a spring 147 between the bottom of the bore and the screw 145 tending to urge the plunger upwardly for pressure engagement of the honing block with the cam shaft, the degree of spring pressure being determined by means of the screw 145. To hold the plunger against rotary movement, screws 148 threading in the body part 135 have key ends 149 engaging in the keyway 150 in the plunger, this keyway being of sufficient length in axial direction to permit the axial movement of the plunger in the bushing 137, an adjustable stop nut 151 on the threaded lower end of the plunger limiting its upper axial movement.

The bearing honing units HB are supported on a plate 152 extending vertically downwardly below the plates 8 and 9 and between the intermediate framework walls 153 and 154 (Figure 2). As shown on Figures 4 and 6, angle bars 155 and 156 are secured to the intermediate walls 153 and 154 respectively against which the plate 152 engages to be held thereto by screws 157 extending through slots 158 in the plate. Extending forwardly from the plate 152 longitudinally thereof is the dovetail rail 159 which engages in the recesses 160 in the bottoms of the bodies 134 of the mounting units HB to be secured thereto in proper position by gib keys 161 which are set into clamping position by screws 162. The plungers of the units HB extend upwardly through the passageway 10 between the plates 8 and 9. With this arrangement the units HB may be accurately set on the plate 152 for alignment of their honing blocks with the bearing surfaces to be honed between the pairs of cams on the cam shaft W.

It is desirable to facilitate the insertion into the machine of the shafts to be honed and to readily remove them from the machine after honing thereof. Provision is therefore made for withdrawing the honing units in radial direction away from the shaft after honing thereof, and to provide ample clearance for insertion of the next shaft to be honed. The supporting plates for the honing sets or rows are therefore made radially shiftable with the honing units thereon. To permit radial shift of the plate 152 which supports the honing units HB, the holes 153 in the plate 152 through which the screws 157 extend are elongated vertically, and the screws extend through the bars 163 on the front of the plate 152 so that the plate will be held by these bars against the angle bars 155 and 156 but will be free to be shifted vertically, the bars 163 engaging against the plate outside of the ends of the gib rail 159.

On the supporting base plate 70 for the honing units HI screw receiving bars 164 are provided to engage the front face of the base plate at the ends of the gib rail 128. Screws 165 extend through the bars and through elongated holes 166 in the base plate to thread into the supporting bars 71 and 72. Likewise the bars 167 on the supporting plate 74 for the holding units HE receive screws 168 which extend through the elongated holes 169 in the plate to thread into the supporting bars 75 and 76. The supporting plates 70 and 74 with the units thereon

are thus slidable toward or away from the shaft W.

Referring to Figures 1 to 4, a shaft 170 extends between and is journaled at its ends in the intermediate walls 153 and 154. Between these walls the shaft mounts a worm gear 171 which is engaged by a worm pinion 172 journaled in a bearing 173 mounted on a wall 174 forming part of the machine supporting framework. On the front wall 177 of the framework is supported a bearing 175 for a shaft 176 having the hand wheel 177 on its outer end and the bevel gear 178 on its inner end. This gear meshes with the bevel gear 179 on the shaft 180 on which the worm pinion 172 is mounted and which meshes the worm wheel 171. Thus upon turning of the hand wheel 177 the shaft 170 will be rotated.

Referring to Figure 2, the shaft 170 mounts at its ends the spur gears 181 and 182 which mesh respectively with gears 183 and 184. Referring to Figures 2 and 6, the gear 183 is mounted on the inner end of a shaft 185 journaled in the intermediate wall 154 and in a boss 186 extending from the bracket 25 on the end wall 12. Between these walls the shaft mounts a bevel gear 187. At the opposite side of the machine the gear 184 drives a bevel gear 188 on the shaft 189 journaled in the framework walls 11 and 153.

At its lower corners the plate 152 has portions 190 projecting laterally outwardly through slots 191 and 192 in the intermediate walls 154 and 153. On these projecting ends of the plate 152 threaded bearings 193 are mounted, through each of which extends a screw shaft 194. The screw shaft at the right side of the machine mounts at its upper end a bevel gear 195 which meshes the gear 187. An arm 196 extending from the bracket structure 25 receives the screw shaft 40 for support and guidance thereof. The screw shaft at the left side of the machine extends through a guide bearing 197 on the intermediate wall 153 and terminates at its upper end in the bevel gear 193 which meshes the gear 188. With the arrangement thus far described, when the handle 177 is turned for rotation of the shaft 170, the screw shafts 194 will be turned in the bearings 193 for vertical movement of the plate 152 to bring the honing units HB on the plate into or out of honing engagement with the bearing surfaces on the shaft to be honed.

Referring to Figures 2 and 3, threaded bearings 199 are secured on the back of the support plate 70 for the holding units HI. Screw shafts 200 engage in the bearings and mount at their lower ends the bevel gears 201 and 202 which mesh with the gears 187 and 188 respectively. The screw shaft 200 at the left side of the machine is guided in a bearing 203 mounted on the intermediate wall 153, and a similar guide bearing is provided on the intermediate wall 154 for the screw shaft at the right side of the machine.

Threaded bearings 204 are secured to the back of the supporting plate 74 for the mounting units HE, screw shafts 205 engaging in these bearings and mounting bevel gears 206 at their lower ends for meshing with the bevel gears 187 and 188 respectively, these screw shafts being guided in bearing structures 207 on the intermediate walls 153 and 154 respectively.

Referring to Figure 1, the drive shafts 91 and 99 which are connected to drive the driving spindles for the master shafts MI and ME, have the keyways 208 and 209 respectively by which the

worm pinions 95 and 101 are connected to the shafts to rotate therewith. Thus, when the hand wheel 177 is turned for rotation of the bevel gears 137 and 138 the screw shafts 200 and 205 will be turned in the bearings 199 and 204 for movement of the plates 76 and 74 of their supports to bring the honing wheels on the units HI and HE into or out of honing position. These supporting plates 76 and 74 will be moved simultaneously with the supporting plate 152 for the bearing honing units HB and thus, by manipulation of the wheel 177 all of the honing units may be simultaneously withdrawn from the honing field to make way for the insertion into the machine of a shaft to be honed, and then the honing units will be simultaneously brought into honing engagement with the surfaces on the cam shaft to be honed. After the honing units have been brought into honing position by manipulation of the hand wheel 177, the motors 104 and 30 are connected in circuit 20 for rotation of the master shafts and the shaft W to be honed, and the axial reciprocation of the shaft W, the springs in the honing units then holding the honing elements against the respective cams and bearing surfaces for simultaneously honing thereof. Referring to Figures 5 and 11, tapered abutment plates 210 on the supporting body 105 for the honing elements HI and HE are adjustable for engagement with the tail frames 118 on the plungers 137 so that the axes of the cam rollers 128 and the axes of the honing wheels 125 will be maintained in the plane of the axis of the respective master shaft and the shaft W to be honed to thus assure uniform and precision honing of the various cam surfaces. The plates 210 are held in an adjusted position as by screws 211 which extend through elongated holes 212 in the plates.

I have thus produced a machine in which all the cam surfaces and bearing surfaces on the cam shaft may be simultaneously honed with accuracy and precision, and in which the various honing units may be readily set into honing position relative to the arrangement of the cams and bearing surfaces on the shafts to be honed.

It is of course to be understood that details of construction and arrangement may be varied through a wide range without departing from the principles of the invention and it is therefore not the purpose to limit the patent granted hereon otherwise than necessitated by the scope of the appended claims.

What I claim is:

1. A machine for honing cam shafts on which the intake and exhaust cams are arranged in pairs and with the cams of the pairs close together, comprising means for supporting the shaft for rotation, means for supporting for rotation a master shaft having cams thereon corresponding with the cams on the shaft to be honed, a row of honing units for the intake cams and a support on which said units may be set into alignment with the respective intake cams, a second row of honing units and a support on which the units may be set for alignment with the exhaust cams, said two rows of units being in separate planes radial to the shaft to be honed but at an angle with each other, a master cam shaft for each row of units to the dimensions of whose cams the respective cams are to be honed by the units, plungers in said units carrying at their inner ends honing elements for engagement with the cams to be honed and at their outer ends having cam rollers for engagement by the cams on the respective master shafts,

and means for rotating said master shafts and the shaft to be honed at the same speed.

5 2. A machine for honing cam shafts on which the intake and exhaust cams are arranged in pairs and with the cams of the pairs close together, comprising means for supporting the shaft for rotation, means for supporting for rotation a master shaft having cams thereon corresponding with the cams on the shaft to be honed, a row of honing units for the intake cams and a support on which said units may be set into alignment with the respective intake cams, a second row of honing units and a support on which the units may be set for alignment with the exhaust cams, said two rows of units being in separate planes radial to the shaft to be honed but at an angle with each other, a master cam shaft for each row of units to the dimensions of whose cams the respective cams are to be honed by the units, plungers in said units carrying at their inner ends honing elements for engagement with the cams to be honed and at their outer ends having cam rollers for engagement by the cams on the respective master shafts, and means for rotating said master shafts and the shaft to be honed at the same speed, and means for axially reciprocating the shaft to be honed.

10 3. A machine for honing cam shafts on which intake and exhaust cams are arranged and spaced apart in pairs with the cams of each pair close together, comprising means for supporting for rotation a shaft to be honed, a row of intake cam honing units and a support therefor on which said units may be aligned with the cams to be honed, a master cam shaft mounted on said support for rotation and having cams thereon in alignment with the intake cams to be honed, a row of exhaust cam honing units and a support on which said units may be set in alignment with the exhaust cams to be honed, a master cam shaft supported for rotation on the support for said exhaust cam honing units and having cams thereon in alignment with the exhaust cams to be honed, each of the units on said supports having a plunger therein supporting at its inner end a honing element for application to the respective surface to be honed and having a cam roller at its outer end for engagement by the corresponding cam on the corresponding master cam shaft, said supports being at an angle with each other to support the units thereon with their plungers in planes extending through the axis of the shaft to be honed, means for rotating said master shafts and the shaft to be honed at the same speed whereby the cams on the master shafts will control the reciprocation of said plungers for engagement of the honing elements with the respective cam surfaces, and means for simultaneously shifting said supports in their planes for withdrawal of the honing elements of the honing units away from the honing zone or for return thereof into the honing zone whereby a shaft to be honed may be readily inserted into the machine for honing or withdrawn from the machine after the honing operation.

15 4. A machine for honing cam shafts on which intake and exhaust cams are arranged and spaced apart in pairs with the cams of each pair close together, comprising means for supporting for rotation a shaft to be honed, a row of intake cam honing units and a support therefor on which said units may be aligned with the cams to be honed, a master cam shaft mounted on said support for rotation and having cams thereon in alignment with the intake cams to be honed, a

row of exhaust cam honing units and a support on which said units may be set in alignment with the exhaust cams to be honed, a master cam shaft supported for rotation on the support for said exhaust cam honing units and having cams thereon in alignment with the exhaust cams to be honed, each of the units on said supports having a plunger therein supporting at its inner end a honing element for application to the respective surface to be honed and having a cam roller at its outer end for engagement by the corresponding cam on the corresponding master cam shaft, said supports being at an angle with each other to support the units thereon with their plungers in planes extending through the axis of the shaft to be honed, means for rotating said master shafts and the shaft to be honed at the same speed whereby the cams on the master shafts will control the reciprocation of said plungers for engagement of the honing elements with the respective cam surfaces, a third set of honing units for honing bearing surfaces on the shaft between cam pairs thereon, a support for said bearing honing units on which they may be set into alignment with the bearing surfaces to be honed, each of said bearing honing units comprising a plunger with a honing element thereon and spring means tending to shift the plunger for engagement of the honing element with the surface to be honed, and means for simultaneously shifting said three supports with the honing units thereon away from the honing zone whereby a shaft to be honed may be readily applied in the machine for honing and removed from the machine after the honing operation.

5. A machine for honing cam shafts comprising a supporting frame, means on said frame for centering a shaft to be honed, a plurality of rows of honing units in radial planes extending through the axis of the shaft to be honed, supports for said rows of honing units on which the units may be set for alignment with the respective surfaces on the shaft to be honed thereby, means for rotating the shaft, means controlling the application of said units to the respective surfaces to be honed thereby, said supports being shiftable in planes parallel with the planes of the rows of honing units supported thereon and means for simultaneously shifting said supports in their respective planes to carry the units thereon away from or into honing position whereby a shaft may readily be inserted for honing or removal after the honing operation.

6. A machine for the purpose described having a supporting frame, means on said frame for centering and rotating a cam shaft to be honed, a first support and honing units thereon for honing some of the cams on the shaft, a second support and honing units thereon for honing other cams on said shaft, a third support and honing units thereon for honing bearing surfaces on the shaft between the cams thereon, and means for simultaneously shifting said supports on said frame to move the honing units thereon away from or into honing position.

7. In a machine for the purpose described, a supporting framework, means on said framework for centering for rotation a shaft to be honed, means for rotating said shaft, a plurality of rows of honing units arranged in planes extending radially relative to the axis of said shaft, each honing unit supporting a honing element for honing engagement with a surface to be honed on the shaft, separate supports on said framework for said rows of honing units, and means for

shifting said supports on said framework for movement of said rows of honing units in their respective planes to carry their honing elements into or out of engagement with the respective surfaces on the shaft to be honed.

8. In a machine for the purpose described, a supporting framework, opposed centering heads on said framework between which a shaft to be honed is centered for rotation, a supporting plate on said framework having a supporting rail thereon extending parallel with the shaft, a row of honing units mounted on said rail, each unit having a plunger therein supporting at one end a honing element and a spring tending to hold said plunger with its honing element against the surface on the shaft to be honed thereby, said units being individually adjustable on said rail for alignment of their honing elements with the particular surfaces on the shaft to be honed thereby, and means for limiting the movement of the unit plungers by their respective springs, said supporting plate being shiftable on said framework, a screw shaft structure connecting said plate with said supporting framework, and means for turning said screw shaft structure for shift of said plate to carry the units thereon into or out of honing position.

9. In a machine for the purpose described, a supporting framework, means on said framework for supporting and centering a shaft to be honed, means for rotating said shaft, a plurality of rows of honing units in planes extending through the axis of the shaft, a supporting plate for each row of honing units, said supporting plates being shiftable on said framework, screw shaft structures between said supporting plates and said framework, and means for effecting simultaneous rotation of said screw shaft structures for simultaneous movement of said supporting plates to carry the honing units thereon into or out of honing position.

10. A machine for honing cam shafts on which intake and exhaust cams are arranged in pairs and with the cams of the pairs close together, comprising means for supporting a shaft for rotation, a row of honing units for the intake cams and a support on which said units are mounted, a second row of honing units for the exhaust cams and a support on which the units are mounted, said two rows of units being in separate planes radial to the shaft to be honed but at an angle with each other whereby all said cams may be honed at the same time.

11. A machine for honing cam shafts on which intake and exhaust cams are arranged in pairs with the cams of the pairs close together and with shaft bearing surfaces between the pairs, comprising means for supporting a shaft for rotation, a row of honing units for the intake cams and a support for said units, a second row of honing units for the exhaust cams and a support for said units, and a third row of honing units for the bearing surfaces and a support for said units, said three rows being in separate planes radial to the shaft to be honed but at an angle with each other whereby all said cams and bearing surfaces may be honed at the same time.

12. A machine for honing cam shafts on which intake and exhaust cams are arranged in pairs with the cams of the pairs close together and with shaft bearing surfaces between the pairs, comprising means for supporting a shaft for rotation, a row of honing units for the intake cams and a support for said units, a second row of

honing units for the exhaust cams and a support for said units, a third row of honing units for the bearing surfaces and a support for said units, said three rows being in separate planes radial to the shaft to be honed but at an angle with each other whereby all said cams and bearing surfaces may be honed at the same time, and means for moving said three supports for radial shifting of the rows of units thereon into or out of honing engagement with said cams and bearing surfaces.

13. A machine for honing cam shafts comprising a supporting table, a head stock and a tail stock mounted on said table for supporting a cam shaft to be rotated, two supports on said table extending upwardly and outwardly therefrom at an angle therewith and at opposite sides of the shaft to be honed, a row of honing units mounted on one of said supports for honing engagement with some of the cams on the cam shaft and, another row of honing units on said other support for honing engagement with other cams on the cam shaft.

14. A machine for honing cam shafts comprising a supporting table, a head stock and a tail stock mounted on said table for supporting a camshaft to be rotated, two supports on said table extending upwardly and outwardly therefrom at an angle therewith and at opposite sides of the shaft to be honed, a row of honing units mounted on one of said supports for honing engagement with some of the cams on the cam shaft, another row of honing units on said other support for honing engagement with other cams on the cam shaft, a third support below said 35

table and a row of honing units thereon projecting upwardly through said table for honing engagement with bearing surfaces between cams on said shaft.

- 5 15. In a machine for honing cam shafts, a supporting framework, a table on said framework, guides extending upwardly and outwardly from said table at opposite sides thereof, supporting means on said table between said guides for the cam shaft to be honed, supports slideable on said guideways, a row of honing units on one of said supports for honing some of the cams on said camshaft and a row of honing units on said other support for honing other cams on the cam shaft, means for sliding said support on said guides for movement of said rows of units in directions radial to the shaft to be honed for movement of said units into or out of honing engagement with the respective cams on the shaft.
- 10 15. In a machine for honing cam shafts, a supporting framework, a table on said framework, guides extending upwardly and outwardly from said table at opposite sides thereof, supporting means on said table between said guides for the cam shaft to be honed, supports slideable on said guideways, a row of honing units on one of said supports for honing some of the cams on said camshaft and a row of honing units on said other support for honing other cams on the cam shaft, means for sliding said support on said guides for movement of said rows of units in directions radial to the shaft to be honed for movement of said units into or out of honing engagement with the respective cams on the shaft.
- 15 16. In a machine for the purpose described, supporting framework for a shaft to be honed, a plurality of rows of honing units spaced around the shaft, a support for each row of honing units, said supports being movable for carrying the units thereon in directions radial of the shaft into or out of honing position, screw shaft structure between said framework and each of said supports, a drive shaft having gearing connection with said screw structure shaft, and means for operating and drive shaft for simultaneous movement of said supports for carrying the honing units thereon into or out of honing position.
